PRESSURE LUBRICATING APPARATUS

Werner Max Josef Jüllig, Stockholm, Sweden, assignor to Sven Magnus Zackarias Tacklind, Stockholm, Sweden

Application December 8, 1930, Serial No. 500,959
In Sweden February 22, 1930

4 Claims. (Cl. 184—32)

With the advance of the lubricating art the requirements of such lubricating apparatus becomes more and more exacting, which having the least possible dimensions are capable of providing a great number of journals and bearings independently of each other with individual quantities of lubricating medium.

With regard to the general construction two characteristic groups of apparatus can be differentiated. One group consists of individual pumps arranged in rows, while in the other group the pumps are arranged concentrically about a driving shaft, and the present invention relates to the last named group. Apparatus of the last named type, which hitherto have been available on the market, are provided with at the most 24 pumps in one aggregate. A greater number of pumps can only be obtained by combining several aggregates. If such an aggregate is provided with more than 12 pumps, the various pumps can no longer be controlled separately and must be set and operated conjointly in pairs. According to the principle of the present invention, practically as many pumps as desired may be arranged in one single aggregate, at the same time maintaining the same advantages for all pumps, and the invention may also be applied to one pump only.

Amongst the lubricating apparatus hitherto employed and having the pumps arranged concentrically may further be distinguished such apparatus in which the pistons by their oscillating movements about their axes effect the closing and opening respectively of the inlet and outlet channels of the pumps. This kind of apparatus, however, has the disadvantage that all pistons exert their pressure movement simultaneously, so that during a fraction of the rotation of the driving shaft the pump work must be carried out for all pistons at one and the same time, whereby the torsional driving moment becomes uneven and the number of pumps is limited on account of the comparatively great stresses on the driving mechanism.

Lubricating apparatus are further known, which are provided with pump pistons arranged concentrically about a driving shaft, the pump pistons coming in operation one after another. However, in such an arrangement, special mechanism is required for controlling the inlet and outlet channels, either in the form of grooves arranged on the central driving shaft or in the form of special control pistons.

The present invention relates to a pressure lubricating apparatus having piston pumps ar-

ranged in circles and working one after the other, the pistons receiving, in a manner known per se, an axial reciprocating pumping movement and at the same time an oscillatory movement about their axes for alternately closing and opening the suction and pressure channels, and the chief characteristic feature of the present invention consists in a single control member operatively connected with the pump pistons and so arranged and so constructed that the pump pistons, solely by means of the said control member, receive both axially reciprocating and oscillatory movements.

A further feature of the present invention consists in that the pump pistons receive their reciprocating and their oscillatory movements by a single member which is adapted to execute a circulary swinging, that is to say a rolling, movement about an inclined axis. A further object of the invention is to provide a driving mechanism for such pump pistons, comprising eccentrically movable (but otherwise non-rotating) means which subjects the pump pistons to both axially reciprocating and also oscillatory movements. By means of these devices it is possible to arrange the pump pistons in several concentric circles about a centrally arranged driving shaft, whereby a very compact construction of comparatively small dimensions is obtained, in which in addition the pump pistons are operated one after another, so that the stresses on the driving mechanism are substantially uniform and on account thereof the driving mechanism may be of small dimensions in comparison with apparatus of this kind hitherto known.

Further features characterizing the invention will be more fully referred to in the following description with reference to the accompanying drawings, in which Fig. 1 shows a vertical section through a pressure lubricating apparatus according to the invention and arranged for 100 pump pistons. Fig. 2 shows the same apparatus in a plan view, in which for the sake of clearness a portion of the casing has been cut away and a number of the pistons have been left out. Fig. 3 shows a section through an apparatus which is provided with one pumping means only. Fig. 4 shows the same apparatus in a lateral view and Fig. 5 shows the same in a plan view, the upper protection cover having been removed. Fig. 6 shows a vertical section through an apparatus having six pump pistons. Fig. 7 shows a plan view of the same apparatus, the upper protecting cover having been removed. Fig. 8 shows a vertical section through an apparatus having like-

wise six pumps, in which, however, the means actuating the pumps is executed in another manner than in the forms of embodiment previously shown. Fig. 9 is a plan view, partly in section, 5 of the apparatus shown in Fig. 8. Fig. 10 shows on a larger scale some details of Fig. 2; Figs. 11 and 12 show respectively an elevation and a plan view of a carrier device illustrated in Fig. 6, the ring 66 being omitted; Figs. 13 and 14 show in 10 similar views a detail pertaining to said carrier device.

According to the form of embodiment shown in Figs. 1 and 2 a pump body composed of the parts 1 and 2, is provided with a plurality of 15 bore holes 3 and 4 respectively for pump pistons which with their axes are arranged in four concentrical circles. The parts 1 and 2 preferably produced of cast iron, surround an annular channel 5, to which is supplied a lubricant from the 20 outside by means of the supply conduit 6. In each one of the bore holes 3 and 4 is placed a pump piston 7 or 8 which is provided with a plate 9 extending at right angles to the axis of the piston 25 and at the upper side provided with a conically or spherically rounded off surface. To these plates are fixed guiding pins 10, the axes of which are eccentrically arranged in relation to the axes of the pistons with an eccentricity δ (Fig. 2). The guiding pins are provided with screw threads 30 11, on which are screwed regulating nuts 12 and locking nuts. According to the illustrated form of embodiment, the part 1 substantially encloses the part 2 which is provided with a central opening in which is fixed a sleeve 13 preferably made 35 of steel. In this sleeve is rotatably journalled a shaft 14 which in the following description will be designated "pump shaft". This pump shaft is at its upper end provided with the flange 15 being in section of wedge-like shape and on its upper surface prolonged to form an inclined shaft end 16. In axial extension of the pump shaft 14, the shaft end 16 is provided with the square part 17 for fastening thereon a hand wheel 20 or the like 40 which serves the purpose to manually operate the pressure lubricating apparatus, if desired. About the inclined shaft end 16 is rotatably journalled a disk which in the following is designated "working disk". The central plane of this working disk passes through points P and O, as shown in Fig. 1. Point P is located on the axis of the shaft end 16 and point O is located on the axis of the pump shaft 14. The inclination of the axis of the shaft end 16 in relation to the axis of the pump shaft 14 is determined in the following manner. 45 50 55 60 65 70 75

When looking upon Fig. 2 there is a line I-II passing through the points P and O and the distance between these two points is the eccentricity ϵ . There is further a diametrical line passing through O, i. e. the axis of the pump shaft 14, and a line III-IV parallel to said diametrical line and passing through point P. Seen in the direction of rotation, according to the arrow ν , the line P-IV is leading with an angle α relative to the line P-II. In this situation of the parts the axis of the inclined shaft end 16 forms an angle α with the axis of the pump shaft 14, when looked upon in Fig. 1. The working disk is provided with steps which decrease as to their height in the direction towards the circumference. The working disk is further provided with longitudinal slots 22, one for each guiding pin 10. The length of these slots is preferably made equal to $2\epsilon +$ the thickness of the guiding pins 10.

The working disk 21 rests against the flange

15 and is kept in its place by means of a washer 23 and a nut 24. The slots 22 and the working disk 21 are arranged in relation to the bore holes 3 and 4 for the pump pistons 7 and 8 in such a manner, that during the motion of the working disk the pump pistons are periodically oscillated to and fro one after the other.

In the parts 1 and 2 are provided suction channels 25, 26 which connect central bore holes in the pump pistons, when these latter occupy 10 certain positions, with the annular channel 5. In a similar way pressure channels 27, 28, 29 and 30 are provided which in certain positions of the pump pistons connect the openings arranged therein with pressure conduits leading 15 to the places of lubrication. Each pump piston is provided with a groove 41 which connects the central bore hole 42 in the pump piston with the outer circumference of the latter, in order to render possible the passage of the lubricating 20 medium from the annular channel 5 to the central bore hole 42 and thence to the discharge channels 27-30.

The pump body 1, 2 with the parts pertaining thereto is mounted on a casing 31, the part 2 being fixed to the casing 31 by means of screw bolts 32. In the casing is arranged a driving mechanism for the pump shaft, which in the present case consists of a ratchet and pawl device. At the bottom of the casing is positioned 30 a plate 37 having a short shaft extending vertically upwardly, on which is rotatably journalled a ratchet wheel 34. The ratchet wheel supports at its upper part a fork-like part 18 which cooperates with a corresponding fork-like part 35 39 on the pump shaft, so that the rotation of the ratchet wheel 34 is directly transferred to the pump shaft. On a hub of the ratchet wheel are rotatably journalled two feeding levers 33 and 33a which at their free ends 38 and 38a are 40 rounded off to form balls and are arranged in an angularly or cam shaped groove 39 on a driving shaft 40. The feeding levers support preferably spring-actuated pawls 35 and 35a which are in engagement with the teeth on the ratchet wheel 45 34. By means of this arrangement it is rendered possible that the driving shaft 40 may rotate in any direction whatever, while the pump shaft always will rotate in the direction required for the special purpose.

The mode of operation of the pressure lubricating apparatus shown in Figs. 1 and 2 provided with a hundred pumps is the following: By rotating the driving shaft 40 in one or the other direction, the feeding levers 33 and 33a receive 55 reciprocating motion, whereby the pawls 35 and 35a alternately will actuate the ratchet wheel 34 and will rotate the latter step by step always in the same direction. By means of the fork-like parts 18, 19 the step-like rotary movement 60 of the ratchet wheel 34 is transferred to the pump shaft 14 and its parts 15, 16. On account of the above described formation of the part 18, the working disc 21 performs a movement which is composed of an oscillating circular movement 65 about the vertical axis of the pump shaft 14 with the eccentricity ϵ (Fig. 2) and a vertical wobbling movement as a consequence of the inclined position of the shaft end 16 at an angle β in relation to the vertical axis.

Inasmuch as the slots 22 in the working disk 21 surround the guiding pins 10 of the pump pistons and as further the eccentricity δ of the guiding pins in relation to the axes of the pistons is greater than the eccentricity ϵ of the 75

point P in relation to the vertical axis of the pump shaft 14, each piston will perform an oscillatory movement to and fro about its axis, the medium position of the plate 9 being tangential in relation to the circle passing through the axes of the pistons. In Fig. 2 such a medium position is indicated at a, an eccentric position in one direction is indicated at b and an eccentric position in the opposite direction is indicated at c. By the oscillatory movement to and fro of the pistons, the groove 41 in the pistons will come into communication alternately with the suction channel 25 and with the pressure channel 27, the lubricating medium passing during the axially reciprocating movement of the piston, through the central bore hole 42 of the latter. The vertical component of the movement of the working disk 21 serves to move the pistons up and down, in that the working disk in moving downward (as shown to the left in Fig. 1) presses against the plates 9 on the pistons and in its movement upwardly presses against the regulating nuts 12. On account of the fact that the vertical components of the movement at different points of the working disk are proportional to the distance between these points and the point P, the pistons arranged at different distances from the central axis would carry out different strokes, in case the working disk had throughout the same thickness. For this reason the working disk is provided, as above indicated, with steps, so that the pistons arranged nearest the circumference of the working disk will receive the same vertical movement as the pistons arranged nearest the central axis. From the above statements it will be seen, that one member only is necessary, in order to subject the pistons partly to a reciprocating pumping movement and partly to an oscillatory movement to and fro for controlling the inlet and outlet channels. This is effected by having the working disk arranged, in the above indicated manner, upon the rotating, but axially non-displaceable pump shaft. By means of this arrangement further the advantage is gained, that the pumps are actuated one after another in order, so that practically a small number of pistons only are actuated at one and the same time, that is to say one on each side of the working disk, whereby the power consumption at each moment is comparatively small and in addition uniformly distributed over a complete revolution of the pump shaft. Thus, the illustrated apparatus having a hundred pistons requires practically no more power than similar apparatus of another construction having only a few pumps. The driving mechanism may thus have very small dimensions in spite of the great number of pumps, which results in the whole apparatus only requiring comparatively small space.

The new arrangement can, however, with the same advantage be applied also to apparatus which are provided with a smaller number of pumps or even with one pump only, because the circumstance that one member only is required for the actuation of the pump pistons, makes it possible that apparatus of this kind may be manufactured considerably easier and cheaper than those, in which for the actuation of the pistons more than one member is required or the driving shaft must be reciprocated in axial direction.

A preferred form of embodiment suitable for one pump piston only is illustrated in Figs. 3-5.

In the pump body 43 is rotatably journalled the pump shaft 44 which at its upper end is extended by a wedge-like flange 45 and an inclined shaft end 46 which at its free end 47 is provided with threads, on which is arranged a washer 48 and the nut 49 to keep the working disk 50 in its correct place. The pump shaft 44 carries at its lower end a worm wheel 51 which is in engagement with a worm 52 on the driving shaft 53. The working disk consists in this case of a single crank and may be considered to constitute a minor portion of the working disk 21 shown in Fig. 1. The slot 56 in the crank and surrounding the guiding pin 54 on the pump piston 55 may in this case consist of a circular hole having a somewhat greater diameter than the diameter of the guiding pin 54. The pump piston 55 is, in a similar manner as before, provided with the conically or spherically rounded off plate 57, and on the guiding pin are arranged regulating and locking nuts 58, 59.

The mode of operation of the apparatus according to this form of embodiment is, with respect to the principle, the same as for the apparatus for a hundred pumps shown in Figs. 1 and 2, but varies from this latter in the following manner. The crank 50 performs a combined movement which is composed of a swinging, up and down movement in a plane passing through the guiding pin and the pump shaft, and of a horizontal movement which is similar to the movement of a connecting rod on a steam engine.

A modified form of embodiment is shown in Figs. 6 and 7 in connection with an apparatus adapted for six pumps. The pumps and their pistons as well as the guiding pins and the working disk are, with respect to their construction, in agreement with corresponding parts shown in Fig. 1. The driving mechanism, however, is similar to that shown in Fig. 3. In order, however, to always obtain the same direction of pumping with various directions of rotation of the driving shaft, provision has been made in this case for a special mechanism which makes the direction of pumping independent of the direction of rotation of the driving shaft. For this purpose the pump shaft 60 is provided with a cylindrical flange 61 on which is eccentrically (with an eccentricity ϵ) arranged a shaft end 62. About this shaft end is rotatably journalled a sleeve 63 which has an outer surface incliningly positioned in relation to the axis of the shaft end, the axis of this outer surface forming an angle β with the axis of the shaft end in the point P. The sleeve is provided with a flange 55 which in section is of wedge-like shape and has a shoulder 64 which extends in the form of a sector about the shaft end about a certain portion of the circumference. On the shaft end is fastened, by means of a pin 65, a ring 66 which is provided with a sector-shaped shoulder 67 which will cooperate with the shoulder 64 when the pump shaft 60 with the shaft end 62 is rotating. By means of this carrier device 64, 67, the direction of pumping always remains the same independently of the direction of rotation of the pump shaft or of the driving shaft 68 driving the latter. On the cylindrical outer surface of the sleeve is rotatably journalled a working disk 69 corresponding to the working disk 21 shown in Fig. 1, which in a similar manner as before is provided with longitudinal slots 70 which surround the guiding pins of the pump pistons.

The mode of operation of the apparatus according to this form of embodiment is the following:

When the driving shaft 68 is subjected to rotation, this rotation is transferred by means of the worm gearing to the pump shaft 60 and thus also to the ring 66 fixed to the shaft end 62. The said 5 ring carries by means of its shoulders 67 the shoulder 64 on the sleeve 63, whereby this latter receives its rotation. Due to the fact that the working disk 69 partly receives an eccentric movement and partly, as a consequence of the outer 10 surface of the sleeve 63 being inclinably positioned, a rocking movement, the working disk will actuate the pump pistons in a similar manner as above described in connection with the form of embodiment shown in Fig. 1. In case the driving 15 shaft 68 is rotating in opposite direction, the pump shaft 60 and thus the ring 66 will also rotate in opposite direction. At the beginning the sleeve 63 will not partake in this reverse rotation, because the shoulder 67 will be removed from the shoulder 64, until the other side of the shoulder 20 67 will abut against the opposite side of the shoulder 64. Under this movement of rotation the sleeve performs an eccentric movement with the eccentricity ϵ , so that the small pump pistons will be turned about their axes. As soon as shoulder 25 67 on the ring 66 contacts with shoulder 64 on the sleeve 63 this latter is carried along, whereby the working disk 69 receives its wobbling motion. On account of the fact that the pistons 30 have been turned about their axes and the working disk is wobbling in opposite direction, the pumps will operate to force the lubricant into the lines as before, that is the pumps operate consecutively regardless of whatever direction the driving 35 shaft may turn.

It is of course also possible to make the apparatus according to Figs. 3-5 reversible, in case the pump shaft 44 with the parts 45 and 46 are carried out in the same manner as illustrated in 40 Fig. 6.

For apparatus having a small number of pumps, for instance 2-4, a working sector may be employed instead of the working disk according to 45 Figs. 1 or 6, and such a form of embodiment may be considered to constitute a construction lying between the device according to Fig. 3 and the device according to Fig. 1. Also in this case the construction as shown in Fig. 6 may be applied.

Figs. 8 and 9 show another modified form of embodiment, in which the pump pistons however are arranged in planes at right angles to the pump shaft. For the sake of simplicity a worm gear driving mechanism has in this case been shown, 50 consisting of the driving shaft 71 and the worm gear 72, but it is obvious that also the driving mechanism shown in Fig. 1 may be utilized in order to make the apparatus reversible, so that the direction of pumping always is the same. In this form of embodiment the pump body consists of the disk-like part 73 which is provided with radial bore holes for the pump pistons 74. The pump pistons are provided with a central bore hole 75 and further on their circumference with a groove 55 in the form of an inclined slot 76. The pistons are for the rest carried out in the same manner as those shown in Fig. 1, that is to say they support a plate 77 which is provided with the guiding pin 78 which in its turn supports the regulating nut 79 and the locking nut 80. The disk-like part 73 is fastened to the pump housing 81 which is mounted on a housing 82 enclosing the driving mechanism. The pump housing 81 is provided with a central opening in which is rotatably journaled the pump shaft 83. The pump shaft is

5 with its other end 84 also rotatably journaled in a bearing 85 arranged at the bottom of the lower housing 82. The pump shaft is provided with an eccentrically arranged cylindrical part 86 on which is rotatably journaled a working disk 87 which in this case has the form of a disk with the edges at the circumference turned up. This turned-up edge of the working disk is provided with slots 88 of the same width as the diameter of the guiding pins 78. These guiding pins are rotatably arranged in said slots, so that the same will follow the movements of the working disk.

10 The lubricating medium is admitted to the pump pistons by suction openings 89 and is pressed out through pressure channels 90 and through 15 the discharge conduits 91. These discharge conduits are united with the pump housing 81 by means of a screw connection 92, a packing device 93 for the discharge conduit being arranged in 20 the pump body 73 proper.

The pump body 73 is provided with guiding 25 ledges 94 and the working disk 87 is provided with similar guiding ledges 95. The guiding ledges on one part are arranged at right angles to the guiding ledges on the other part. Between the said four guiding ledges is slideably arranged a guiding member 96 of square form. By means of this 30 guiding device all relative rotary motion between the pump body 73 and the working disk 87 is prevented but a relative oscillatory circular movement of the working disk is permitted.

The apparatus according to this form of embodiment works in a similar manner to those above described. The pump pistons receive the movements from the working disk 87. This latter performs on account of its support on the eccentric part 86 of the pump shaft 83, 84 and on account of its parallel guiding by means of the guiding member 96, an oscillatory circular movement. It carries the pump pistons partly in 40 the direction of the longitudinal axes of the latter, in that the turned-up edge of the working disk alternately presses against the plate 77 on the pump pistons and against the regulating nuts 79, and partly subjects the pump pistons to an 45 oscillatory movement to and fro, in that the slots 88 of the working disk carry along the guiding pin 78 in tangential direction. By means of this combined movement of the pump pistons the groove 76 is alternately brought in connection 50 with the inlet opening 89 during the suction stroke and with the discharge channel 90 during the pressure stroke. The groove in the piston may preferably be produced by cutting a slot by means of a straight cutter inclined in relation to the 55 axis of the pistons.

Also in this case the pump pistons are actuated one after another, so that the driving power is uniformly distributed over one revolution of the pump shaft.

In all forms of embodiment the control of the piston strokes is effected in a manner known per se by adjusting the position of the regulating nuts.

What I claim is:—

1. A forced lubrication apparatus comprising a drive shaft provided with a crank, a plurality of pumps arranged in spaced relation to one another around said shaft and disposed at right angles to the latter, said pumps including combined piston and valve members, a thrust disc journaled on said crank and having an upwardly directed peripheral wall, eccentrically disposed guide pins on the pump pistons, said peripheral wall having notches therein receiving said pins, 75

and means guiding said thrust disc whereby, during rotation of the drive shaft, said disc is revolved around the axis of said shaft without rotation about its own axis, those components of the movement of the disc coinciding with the piston and valve members causing the latter to reciprocate axially, and the components at right angles to the first mentioned components causing the pistons to oscillate angularly about their axes.

10 2. A forced lubrication apparatus as claimed in claim 1, characterized in that the guide means for the thrust disc is constituted by a pair of guiding ledges disposed parallel with each other on the thrust disc and a second pair of guide ledges disposed at right angles to the first pair and carried by a relatively stationary part of the

apparatus, and a square guiding plate slidably arranged between the two pairs of guiding ledges.

3. A forced lubrication apparatus as claimed in claim 1, characterized by the provision of a laterally extending plate connecting each piston and valve member with its guide pin, the surfaces of said plates cooperating with the thrust disc being rounded whereby the axis of the circumscribed cone is parallel with the axis of the respective piston member.

10 4. A forced lubrication apparatus as claimed in claim 1, characterized in that said thrust disk is caused to perform its revolving motion in a plane at right angles to the axis of said drive shaft.

15 WERNER MAX JOSEF JÜLLIG.
